PROJECTION TUBE WITH ELECTRICALLY
MOVABLE TARGET ELECTRODE

Victor Trad, Asbury Park, N. J.

Original application March 15, 1952, Serial No. 276,756, now Patent No. 2,637,829, dated May 5, 1953. Divided and this application May 4, 1953, Serial No. 352,647

7 Claims. (Cl. 313—92)

1

This invention relates to a television projection tube such as may be used for the purpose of displaying images upon a large television screen.

This application is a divisional of patent application Serial No. 276,756, filed March 15, 1952, entitled: "Projection Tube with Movable Target Electrode" and issued May 5, 1953, as Patent No. 2,637,829.

An object of the present invention is to provide a television projection tube having a built-in optical system, together with a method of mechanically focusing said tube for different projection throws, by means of small electrical motors sealed within the tube envelope.

The invention consists of the construction, combination and arrangement of parts, as herein illustrated, described and claimed.

In the accompanying drawings, forming a part hereof, is illustrated one embodiment of the invention, in which drawings similar reference characters designate corresponding parts, and in which:

Figure 1 is a somewhat diagrammatic view in front elevation of a projection tube, in accordance with the present invention.

Figure 2 is a fragmentary view in side elevation, somewhat enlarged, of the tube focusing device, as shown in Figure 1.

Figure 3 is a longitudinal section of a projection tube having attached thereto a focusing device, somewhat enlarged for the sake of clarity, according to this invention.

Referring to the drawings, 10 indicates a sealed glass envelope, such as may be used in connection with a cathode ray tube. An ion gun 11, such as is carried in the rear of such tube 10, is directed at the face thereof. The front 12 of the tube 10 comprises a flat transparent surface at the center of which there is carried the focusing device, generally indicated at 13. The focusing device 13 is adapted to move a phosphor-coated face plate 14, as hereinafter set forth.

Between the face plate 14 and the ion gun 11, there is provided the well known anode ring 15. The rear surface 16 of the envelope 10 is polished and mirrored, and optically ground to provide the curved reflecting surface of the well known "Schmidt" optical system. Inasmuch as this surface is contained within the vacuum of the tube 10, the necessity for cleaning the surface is thereby eliminated. When the tube is in operation, electrons from the ion gun 11 strike the phosphor-coated face plate 14, forming an image upon the said plate. In the present embodiment of the invention, the image is taken from

2

the striking side of the face plate 14, and projected upon the mirrored surface at the rear of the tube.

In order to adapt the tube for use over a variety of focal distances, it is necessary to provide some means for changing the position of the face plate 14. Accordingly, a bracket 17 is secured to the inner surface of the face 12 of the tube 10. The bracket 17 is adapted to hold, in a manner hereinafter described, the face plate 14. The face plate thus held may be adjusted vertically, laterally, and longitudinally.

The motion imparted to the face plate 14 stems from the operation of three small motors 18, 19 and 20, located within the envelope of the tube 10. Motors 19 and 20 are provided with worms 21, secured to the shafts thereof, which worms engage a face plate support member 22. By energizing the motors 19 and 20 there may be imparted to the support 22 a suitable motion across the front of the plate 12 of the tube 10, in any direction. The face plate supporting bracket 17 carries at the center thereof a worm 23, which worm is threadably engaged with the face plate 14, as shown in Figure 2. The motor 18 is adapted to drive a small gear 24, which is in mesh with a larger gear 25, coupled to the worm 23, by means of a key 26.

A pin 27 is inserted within a suitable opening 28 in the rear of the face plate 14, to prevent said face plate from rotating when the motor 18 turns the gears 24 and 25, thereby causing the worm 23 to enter or leave the back of the plate 14, as the case may be.

Knobs 29 and 30, shown on the outside of the face plate 12 in Figure 2, are connected to switches 31 and 32, which switches in turn activate the motors 18, 19, 20, respectively. The motors 18, 19, 20 are supplied with current from a suitable source (not shown) by means of leads 33 which traverse the front plate 12, and are sealed therein so as not to interfere with the vacuum of the tube 10.

From the foregoing, it will be seen that all of the necessary motions requisite to focus and orient the image coming from the ion gun 11, may be provided by the manipulation of the knobs 29 and 30, located on the outside of the tube 10.

Having thus fully described the invention, what is claimed as new, and desired to be secured by Letters Patent of the United States, is:

1. A television image projection tube comprising, a sealed envelope, a transparent front wall on said envelope, a rear wall, an ion gun carried

by the rear wall of the envelope so that its ion stream is directed toward the front wall, a faceplate movably held within the envelope to receive and translate the ion stream into an image, a reflecting surface upon the rear wall adapted to receive and transmit the image from the faceplate, a source of electrical potential, switch means connected to the electrical potential source, motors, carried within the envelope and connected to the switch means, said motors being mechanically coupled to the faceplate whereby the position of the faceplate within the tube may be changed so as to focus and orient the image without disturbing the seal of the said tube.

2. A television image projection tube comprising, a sealed envelope, a transparent front wall on said envelope, a rear wall, an ion gun carried by the rear wall of the envelope so that its ion stream is directed toward the front wall, a faceplate, a worm threadably inserted into the faceplate, said worm being movably held within the envelope, said faceplate being constructed so as to receive and translate the ion stream into an image, a reflecting surface upon the rear wall adapted to receive and transmit the image from the faceplate, a source of electrical potential, switch means connected to the electrical potential source, motors, carried within the envelope and connected to the switch means, said motors being mechanically coupled to the faceplate whereby the position of the faceplate within the tube may be changed so as to focus and orient the image without disturbing the seal of the said tube.

3. A television image projection tube comprising, a sealed envelope, a transparent front wall on said envelope, a rear wall, an ion gun carried by the rear wall of the envelope so that its ion stream is directed toward the front wall, a faceplate movably held within the envelope to receive and translate the ion stream into an image, a reflecting surface upon the rear wall adapted to receive and transmit the image from the faceplate, a source of electrical potential, switch means connected to the electrical potential source, motors, carried within the envelope and connected to the switch means, said motors being mechanically coupled to the faceplate by a bracket whereby the position of the faceplate within the tube may be changed so as to focus and orient the image without disturbing the seal of the said tube.

4. A television image projection tube comprising, a sealed envelope, a transparent front wall on said envelope, a rear wall, an ion gun carried by the rear wall of the envelope so that its ion stream is directed toward the front wall, a faceplate movably held within the envelope to receive and translate the ion stream into an image, a reflecting surface upon the rear wall adapted to receive and transmit the image from the faceplate, a source of electrical potential, switch means connected to the electrical potential source, control knobs carried upon the outside face of the front wall to operate the switch means, motors, carried within the envelope and connected to the switch means, said motors being mechanically coupled to the faceplate whereby the position of the faceplate within the tube may be changed so as to focus and orient the

image without disturbing the seal of the said tube.

5. A television image projection tube comprising, a sealed envelope, a transparent front wall on said envelope, a rear wall, an ion gun carried by the rear wall of the envelope so that its ion stream is directed toward the front wall, a faceplate movably held within the envelope to receive and translate the ion stream into an image, a reflecting surface upon the rear wall adapted to receive and transmit the image from the faceplate, a source of electrical potential, switch means secured to the outside face of the front wall connected to the electrical potential source, motors, carried within the envelope and connected to the switch means, said motors being mechanically coupled to the faceplate whereby the position of the faceplate within the tube may be changed so as to focus and orient the image without disturbing the seal of the said tube.

6. A television image projection tube comprising, a sealed envelope, a transparent front wall on said envelope, a rear wall, an ion gun carried by the rear wall of the envelope so that its ion stream is directed toward the front wall, a faceplate, a worm threadably inserted into the faceplate, said worm being movably held within the envelope, said faceplate being constructed so as to receive and translate the ion stream into an image, a reflecting surface upon the rear wall adapted to receive and transmit the image from the faceplate, a source of electrical potential, switch means connected to the electrical potential source, control knobs carried upon the outside of the front wall to operate the switch means, motors, carried within the envelope and connected to the switch means, said motors being mechanically coupled to the faceplate by a bracket whereby the position of the faceplate within the tube may be changed so as to focus and orient the image without disturbing the seal of the said tube.

7. A television image projection tube comprising, a sealed envelope, a transparent front wall on said envelope, a rear wall, an ion gun carried by the rear wall of the envelope so that its ion stream is directed toward the front wall, a faceplate movably held within the envelope to receive and translate the ion stream into an image, a reflecting surface upon the rear wall adapted to receive and transmit the image from the faceplate, a source of electrical potential, switch means connected to the electrical potential source, motors, carried within the envelope and connected to the switch means by leads sealed within the wall of the tube, said motors being mechanically coupled to the faceplate whereby the position of the faceplate within the tube may be changed so as to focus and orient the image without disturbing the seal of the said tube.
